DESIGN FOR A MIXING DEVICE

Henry Gilbert, North Hollywood, Calif., assignor
to Bendix Aviation Corporation, South Bend,
Ind., a corporation of Delaware

Application March 5, 1945, Serial No. 118,258

Term of patent 7 years

(Cl. D44—1)

To all whom it may concern:

Be it known that I, Henry Gilbert, a citizen of the United States, residing at North Hollywood, in the county of Los Angeles and State of California have invented a new, original, and ornamental Design for a Mixing Device, of which the following is a specification, reference being had to the accompanying drawing forming a part thereof.

Fig. 1 is a plan view of a mixing device showing my new design; and

Fig. 2 is a side elevational view of the mixing device shown in Fig. 1.

I claim:

The ornamental design for a mixing device, as shown.

HENRY GILBERT.
